UNITED STATES PATENT OFFICE.

EDSON O. SESSIONS, OF CHICAGO, ILLINOIS.

HIGH-TENSION LOCKING-SWITCH.

1,320,992.

Specification of Letters Patent.

Patented Nov. 4, 1919.

Application filed September 6, 1917. Serial No. 189,923.

To all whom it may concern:

Be it known that I, EDSON O. SESSIONS, a citizen of the United States, residing at Chicago, in the county of Cook and State 5 of Illinois, have invented a certain new and useful Improvement in High-Tension Locking-Switches, of which the following is a specification.

My invention relates to an improved form 10 of high tension locking switch adapted for convenient, safe and effective operation.

With the great advance made in the art of transmitting and using electric current, the need has arisen for switching devices which 15 will not only be applicable to alternating current circuits of high potential, but which also must be positive in operation, and which may be positively locked in closed position, so as to be prevented from accidentally 20 opening the circuit, should the current flowing through the switch be abnormally increased for any reason. Switching devices of this kind are required for as high as 110,000 volts or higher and frequently must 25 have a carrying capacity of 100 amperes or more and for such service the insulating units employed must necessarily be of large dimensions and the length of the switch blade must be correspondingly large to pro- 30 vide a perfectly safe construction, which will not only carry the necessary current when the switch is closed, but will also positively and safely open the high tension circuit when the switch is open.

My invention relates to a switch of this 35 type and contains novel features of construction, a preferred embodiment of which is shown in the accompanying drawings in which,

Figure 1 shows in side elevation a complete switching mechanism,

Fig. 2 shows in front elevation the switching mechanism shown in Fig. 1,

Fig. 3 is an enlarged sectional view of the 45 parts shown in Fig. 1 taken along the line 3-3,

Fig. 4 is a detail view of the operating tool employed in connection with the switch,

Fig. 5 is an enlarged sectional view of the 50 locking mechanism, and

Fig. 6 is a view of a modified base construction.

Similar numerals refer to similar parts throughout the several views.

As shown in Figs. 1, 2 and 3 the switch 55 construction consists of two base clamps 10 and 11 for supporting the insulators 12 and 13, the base clamps being rigidly connected together by metal rods or tubes 14 so that the clamps 10 and 11 are rigidly and permanently held at a proper distance from each other and in proper alinement with each other, thus preventing the improper placing 60 of the insulators 12 and 13 relatively to each other. This is an important feature 65 of my construction, as it results in positively supporting the switching mechanism so that the switch blade will at all times properly engage the contact clips when the switch is mounted for use since the entire 70 structure is assembled in the factory and therefore constitutes a unitary structure which is preferably shipped and installed without disassembling any of the parts.

The insulator 12 has rigidly secured to its 75 outer end in any desired manner a pivot clip 15 to which the lower end 16 of the switch blade is pivotally secured. The portion 16 is rigidly secured to a metal tube or rod 17 of good conducting material, such 80 as copper, which carries at its other end a contact block 18 arranged to engage the contact clip 19 carried by the outer end of the insulator 13 in any desired manner.

The contact block 18 has secured to its 85 upper end a lock casing 20 from which a locking latch 21 extends into engagement with a catch 22 mounted adjacent the contact clip 19 and in electrical connection therewith, when the switch is in its closed 90 position. The contact clip 19 is connected with one of the conductors 23 of the electrical circuit by a connecting clip 24 secured to an extension formed on the catch 22 in the manner indicated, the relation of 95 the parts being such that the projecting portion of the latch 21 and the catch 22 are located below the connector clip 24 permitting the edge of the casing 20 to lie immediately adjacent the outer surface of the connector clip 24. This arrangement results in utilizing the available space to the best 100 advantage and facilitates the employment of the particular construction of lock casing indicated as a result of which the su- 105 perior results described below are secured.

As shown in Fig. 5 the lock casing 20 is hollow or recessed to contain the latch 21

which is pivotally mounted in said casing on a pivot rod 25 and is extended beyond said pivot upwardly and obliquely to the left to overlap an opening 26 formed through 5 the casing. The opening 26 extends upwardly and to the right in an oblique direction from the left hand end of the latch 21 and is provided with a side opening 27 to permit moving the operating tool into and 10 from the opening 26. A separating wall 28 extends from the upper end of the casing 20 to inclose the opening 26 at its upper end and also to limit the side opening 27 so as to restrict the size of the side opening and 15 the upper surface of this wall 28 extends upward and to the right in an oblique direction nearly, or quite to a sharp point at the upper end of the casing since the right hand surface of the casing is substantially vertical. The upper end of the opening 26 thus formed constitutes a seat for engaging the operating tool so that the switch may readily be moved thereby to its closed position. On the lower side of the opening 27 an ex- 20 tending curved wall 29 is formed projecting beyond the line of the inclined upper surface of the casing so that when the operating tool is placed upon the upper surface of the casing and drawn downwardly it is 25 directed by the curved wall 29 through the side opening 27 into the opening 26 to a position to engage the left hand end of the latch 21 for which position a downward pull on the operating tool moves the latch around 30 to the left on its pivot 25 against the action of a compression spring 30 provided in the casing to hold the latch 21 in engagement with the catch 22. After the latch is 35 removed from engagement with the catch by 40 the downward pull referred to, continued motion of the operating tool moves the switch blade from engagement with the contact clip 19 thereby opening the circuit.

As shown in Fig. 3 the contact clip 19 consists of relatively thin contact bars 19^a mounted within rigid protecting brackets 19^b so that the contact bars 19^a may be relatively long and have considerable outward flare at their outer ends to take care to the 45 best advantage of arcing that may develop and to insure proper engagement between the contact block 18 of the switch blade and the contact clip, without danger of the contact bars being accidentally bent to an im- 50 proper position.

The operating tool employed in connection with this switch is preferably constructed as shown in Fig. 4 and consists of a metal loop 31 mounted on the upper end of a rod 60 32 of insulating material such as wood, the lower end of said rod having rigidly secured thereto a handle 33 which preferably is of metal and in the form of a loop in the plane of the loop 31. The loop 31 is of such size 65 as to freely encircle the contact clip 19 dur-

ing the operation of placing the loop 31 in position in the opening 26 of the lock casing, which is accomplished as follows:

The operating tool is held by the operator by means of the handle 33 so that the loop 31 70 is nearly parallel with the plane of the base of the switch and the loop 31 is placed in such vertical position as to pass over the contact clip 19 so that the upper member of the loop 31 rests against the conductor 23. The 75 tool is then drawn outward along the conductor 23 and as a result of the pointed open end of the lock casing being immediately adjacent the wall of the connector clip 24 of the loop 31 slides down the upper end of the 80 lock casing and into the side opening 27 thus into the opening 26 in the lock casing. Bearing in mind that switches of this kind are frequently of considerable size, say for example four or five feet high and that in 85 view of the voltage with which they are employed, they must be placed so that the operator cannot accidentally approach too near for safety to the switching mechanism, the advantage of my improved construction 90 of operating tool and locking mechanism will be apparent. Where it is attempted to use locking devices heretofore known in the art for this particular purpose it is a difficult thing to secure the necessary registry be- 95 tween the end of the operating tool and the eye formed in the lock casing to receive the same on account of the distance of the locking mechanism. For switches of smaller size where the voltage is not as high as that 100 referred to above, the support for the insulators of the switch need not be built up as indicated in Fig. 1, but may be made of a one piece casting as indicated in Fig. 6 at 14^a which construction, of course, secures all 105 of the advantages of rigidly and properly supporting the insulators relatively to each other pointed out in connection with the construction of Fig. 1.

While I have shown my invention in the 110 particular embodiment above described it will be understood that I do not limit myself to this exact construction, as I may employ equivalents thereof known to the art at the time of the filing of this application 115 without departing from the scope of the appended claims.

What I claim is:

1. In a switching mechanism, the combination of a pivot clip, a contact clip, means 120 for supporting said clips at a fixed distance from each other, a switch blade pivoted to the pivot clip and engaging the contact clip when the switch blade is in its closed position, a lock casing carried by the free end 125 of the switch blade, a latch pivotally mounted in said casing, a catch mounted adjacent said contact clip for engaging said latch, and a conductor extending from said contact clip adjacent said casing, said casing 130

having an opening for receiving an operating tool and an inclined surface terminating adjacent said conductor for engaging and directing an operating tool into said 5 opening when said operating tool is moved along said conductor toward said casing.

2. In a switching mechanism, the combination of a pivot clip, a contact clip, means for supporting said clips at a fixed distance 10 from each other, a switch blade pivoted to the pivot clip and engaging the contact clip when the switch blade is in its closed position, a lock casing carried by the free end of the switch blade, a latch pivotally mounted 15 in said casing, a catch mounted adjacent said contact clip for engaging said latch, and a conductor extending from said contact clip adjacent said casing, said casing having an opening for receiving an operating 20 tool and an inclined surface terminating adjacent said conductor for engaging and directing an operating tool into said opening when said operating tool is moved along 25 said conductor toward said casing, said latch having an operating portion overlapping said opening and a spring tending to hold said latch in its engaging position.

3. In a switching mechanism, the combination of a pivot clip, a contact clip, means 30 for supporting said clips in fixed relation relatively to each other, a switch blade pivoted to said pivot clip and engaging said contact clip when said blade is in its closed position, a locking latch carried by the free 35 end of said blade, a catch mounted adjacent said contact clip for engaging said latch when said switch blade is closed, a conductor extending from said contact clip, and a directing bracket carried by the free end 40 of said switch blade having an inclined surface terminating adjacent said conductor when said switch blade is in its closed position to engage and direct an operating tool into releasing engagement with said latch 45 when said tool is moved along said conductor toward said inclined surface.

4. In a switching mechanism, the combination of a pivot clip, a contact clip, means for supporting said clips in fixed relation 50 relatively to each other, a switch blade pivoted to said pivot clip and engaging said contact clip when said blade is in its closed position, a locking latch carried by the free end of said blade, a catch mounted adjacent 55 said contact clip for engaging said latch when said switch blade is closed, a conductor extending from said contact clip, and a directing bracket carried by the free end of said switch blade having an inclined surface 60 terminating adjacent said conductor when said switch blade is in its closed position to engage and direct an operating tool into releasing engagement with said latch when said tool is moved along said conductor toward 65 said inclined surface, said bracket hav-

ing a recess for receiving said operating tool to move said switch blade to its closed position and a guiding wall for preventing motion of said tool from its latch releasing position.

5. In a switching mechanism, the combination of a pivot clip, a contact clip, means for supporting said clips at a fixed distance from each other, a switch blade pivoted to the pivot clip and engaging the contact clip 70 when the switch blade is in its closed position, a lock casing carried by the free end of the switch blade, a latch pivotally mounted in said casing, a catch mounted adjacent said contact clip for engaging said latch, and a conductor extending from said contact clip adjacent said casing, said casing having an opening for receiving an operating tool and an inclined surface terminating adjacent 75 said conductor for engaging and directing an operating tool into said opening when said operating tool is moved along said conductor toward said casing, and an operating tool comprising an insulating handle and a metal loop carried by the end of said handle, 80 said loop being conformed to surround said contact clip when said loop is brought into engagement with said inclined surface.

6. In a switching mechanism, the combination of a pivot clip, a contact clip, means 85 for supporting said clips in fixed relation relatively to each other, a switch blade pivoted to said pivot clip and engaging said contact clip when said blade is in its closed position, a locking latch carried by the free 90 end of said blade, a catch mounted adjacent said contact clip for engaging said latch when said switch blade is closed, a conductor extending from said contact clip, and a directing bracket carried by the free end of 95 said switch blade having an inclined surface terminating adjacent said conductor when said switch blade is in its closed position to engage and direct an operating tool into releasing engagement with said latch when said tool is moved along said conductor toward 100 said inclined surface, and an operating tool comprising an insulating handle and a metal loop carried by the end of said handle, said loop being conformed to surround said contact clip when said loop is brought into engagement with said inclined surface.

7. A tool for operating a locking switch comprising an insulating handle and a metal loop carried by the end of said handle, said 110 loop being conformed to surround the clip contact of a switch when said loop is being moved into engagement with the locking mechanism of said switch.

8. A tool for operating a locking switch comprising an insulating handle and a metal loop carried by the end of said handle, said 115 loop being conformed to surround the clip contact of a switch when said loop is being moved into engagement with the locking 120 mechanism of said switch.

mechanism of said switch, and a handle carried by the other end of said rod, said handle being in the form of a loop to control the angular adjustment of said handle and operating loop.

9. In a locking switch, the combination of a pivot clip, a contact clip, means for supporting said clips in fixed relation relatively to each other, a switch blade pivoted to said pivot clip and engaging said contact clip when said switch blade is in its closed position, a bracket carried by the said switch blade, a latch pivotally mounted on said bracket, and a catch for engaging said latch when said switch blade is in its closed position, said bracket having an opening therethrough extending obliquely across said bracket and communicating with a side opening for receiving an operating tool, said bracket having an outer oblique surface terminating in said side opening and the opposite wall of said opening being extended outwardly to direct an operating tool into said side opening.
10. In a locking switch, the combination of a pivot clip, a contact clip, means for supporting said clips in fixed relation relative to each other, a switch blade pivoted to said pivot clip and engaging said contact clip when said switch blade is in its closed position, a bracket carried by the said switch blade, a latch pivotally mounted on said bracket, and a catch for engaging said latch when said switch blade is in its closed position, said bracket having an opening therethrough extending obliquely across said bracket and communicating with a side opening for receiving an operating tool, said bracket having an outer oblique surface terminating in said side opening and the opposite wall of said opening being extended outwardly to

direct an operating tool into said side opening, said latch having a projecting portion overlapping said oblique opening and a spring tending to hold said latch in its catch 45 engaging position.

11. In a switching mechanism, the combination of a pivot clip, a contact clip, means for supporting said clips in fixed relation relatively to each other, a switch blade pivoted to said pivot clip and engaging said contact clip when said blade is in its closed position, locking mechanism for holding said switch blade in its closed position, a fixed guiding member, and a directing bracket 50 carried by said switch blade having an inclined surface terminating said guiding member to engage and direct an operating tool into releasing engagement with said locking mechanism when said tool is moved 60 along said guiding member toward said inclined surface.

12. In a switching mechanism, the combination of a pivot clip, a contact clip, means for supporting said clips in fixed relation 65 relatively to each other, a switch blade pivoted to said pivot clip and engaging said contact clip when said blade is in its closed position, locking mechanism for holding said switch blade in its closed position, a conductor 70 extending from said contact clip, and a directing bracket carried by said switch blade having an inclined surface for engaging and directing an operating tool into releasing engagement with said locking mechanism when said tool is moved along said conductor toward said inclined surface.

In witness whereof I hereunto subscribe my name this 25th day of August, A. D. 1917.

EDSON O. SESSIONS.
